UNITED STATES PATENT OFFICE.

ANDREW J. CARMICHAEL, OF NEW HAVEN, CONNECTICUT, ASSIGNOR TO THE GREIST MANUFACTURING COMPANY, OF NEW HAVEN, CONNECTICUT, A CORPORATION OF CONNECTICUT.

BASE FOR PORTABLE LAMPS.

Application filed September 26, 1927. Serial No. 222,168.

This invention relates to bases for portable lamps, and more particularly to devices of this character having clamping means normally concealed in the base for firmly attaching the base to a suitable support.

The invention is concerned with and comprises an organization in which the various parts of the base, including the clamping member, the clamping member spring, the weight within the base and other related parts are so designed that they may be disassembled or re-assembled with ease, whereby the various parts may be repaired or replacements readily made, without the employment of skilled labor. Other important features of the invention, such as novel details of construction, and combinations of elements will be better understood and appreciated from the following description, and the aforesaid elements of novelty will be pointed out in the appended claims.

In the accompanying drawings, which illustrate a preferred form of the invention,

Figure 1 shows, in side elevation, a lamp base embodying the invention, and assembled with a lamp socket and bulb to form a complete lamp;

Figure 2 is a longitudinal sectional view through the lamp base and standard;

Figure 3 is an inverted plan view of the inner metal frame for the base and

Figure 4 is a plan view of the socketed nut for receiving the clamping spring.

The lamp base as an entirety is in the form of a hollow, truncated cone. It comprises an inner metal frame member 3, preferably formed of a disk of metal, herein shown provided with a plurality of radial slits 4, representing cut out portions of the metal blank to facilitate shaping the disk into conical form, and a center aperture 6 provided with a notch 6^a; a flat washer 8 fitting within the frame 3; a lower, shaped circular member 10 lying beneath the washer 8 and having depending portions which fit the interior contour of the frame 3; an additional circular, cupped member 12, located below and fitting within the member 10; and a sheet metal exterior base covering 14. This sheet metal portion of the base is surmounted by a washer 16 which fits about and is shaped to the upper extremity of the sheet metal cover 14, and said cover is

provided with a central opening having a projection to fit within the notch 6^a and prevent relative rotation of the parts 3 and 14.

55

The elements 3, 8, 10 and 12 are arranged to be clamped together to form a rigid structure with the sheet metal exterior base covering member 14.

The lamp standard 18 comprises a tube 60 having at its upper extremity two upstanding ears 20, perforated at 21 to receive a bolt 22 which pivotally secures the lamp socket S to the standard. An ornamental enclosing tubular member 24 is supported at its lower end upon the washer 16, and at its upper end engages the lower face of a thickened washer 26 having a central aperture to receive the tubular standard 18, which latter is provided with an annular bead or shoulder 27 engaging 70 the upper edge or face of the washer 26, as shown in Figure 2. The hollow standard 18 passes through central apertures in washer 16, frame member 3, sheet metal covering 14, washer 8, and annular disks 10 and 12, and the lower end of the standard projects beyond the latter disk and is provided with an exterior screw thread. A hollow internally threaded nut 26 engages this thread, and the inner face of the nut bears against the lower 80 face of the disk member 12 when the parts are assembled. The nut 26 is provided with a central aperture through which passes a rod 28. The upper end of this rod is provided with a head 29, and a spiral spring 30 surrounds the 85 rod and is confined between the head 29 thereon and an internal shoulder 32 in the nut 26. The lower end of the rod projects beyond the nut and passes through an aperture in a plate 34, to which plate is secured a wire frame 33, covered by rubber or other cushioning material 35. The parts 34, 33 and 35 constitute a clamp which is normally drawn up into the hollow base by the spring 30. By pulling the clamp out from the base as shown 90 in Figure 1 it may be passed beneath the edge of a table, or other support, and released, whereby the expansive force of the spring 30 will firmly clamp the lamp base to the support.

A felt or other soft washer 38, interposed between the plate 34 and the lower face of the nut 26, acts as a cushioning member between these parts.

100

It will be observed that when the several parts as above described have been assembled, the spring 30 will be held under a slight amount of compression between the internal shoulder 32 of the nut and the head 29 on the rod 28, and the clamp will then be drawn within the base and concealed thereby. The parts are held in clamped relation with each other by the engagement of the nut with the lower disk and the tubular standard, and by engagement between the shoulder 27, washer 26, tubular member 24, washer 16, and the various parts constituting the hollow base, as above pointed out. By screwing the standard into the nut when the parts have been properly combined, all of said parts are tightly clamped together. By unscrewing the standard from the nut various parts of the base and standard may be disassembled with speed and facility, and without disturbing the assembly of the clamp, hollow nut, rod and spring which parts are removable and replaceable, as a unit. The frame member 3 and the annular members 8, 10 and 12, afford, when assembled, sufficient weight to maintain the lamp in upright position against ordinary shocks or disturbing causes, while the clamp permits the lamp to be firmly attached to a suitable support whether the same be horizontal, inclined, or vertical.

The metal covering 14 preferably has its lower edge inturned at 40 to form a groove for receiving a spring wire member 41 which is within a rubber casing 42. This cushioning wire prevents scratching or otherwise marring a polished or finished surface upon which the lamp may be supported, and as the clamp is similarly protected by a rubber covering 35, all portions of the lamp base that might contact with a finished surface are prevented from marring the same.

From the above description it is believed that the advantages of the invention and benefits to be derived from the same will be apparent without further explanation. Changes may be made in the details of construction, or in the relative arrangement of some of the parts without departing from the invention, provided that such changes are within the scope of the following claims.

I claim:

1. A lamp base comprising in combination a hollow member, a tubular standard passing therethrough, a rod reciprocally mounted within said standard and provided with a spring, a hollow nut threaded to the lower end of the standard and having an annular shoulder upon which one end of the spring is seated, and a clamp carried by the lower end of said rod.

2. In a device of the class described, a hollow base member, a weight within said member, a tubular standard extending into said base, a hollow nut provided with an internal shoulder and threaded to the lower end of the

standard, a rod within said standard, a spiral spring on said rod confined between said shoulder and a projection on the rod, and a clamping member carried by said rod.

3. In a device of the class described, a hollow base comprising a shell member and a plurality of internal members constituting a weight, said members being centrally perforated, a hollow standard extending through the perforations in said members and said base, a hollow nut threaded to the extremity of said standard within the base and bearing against one of said members, a tubular member surrounding said standard, said member supported upon the base, an annular washer surrounding said standard and bearing upon said tubular member, and a projection upon the standard engaging said washer whereby the several parts may be firmly clamped together when the nut is screwed upon said hollow standard.

4. In a device of the class described, the combination of a hollow conical frame member, an annular washer within said member, a circular member below said washer, a standard extending through apertures in said members, a nut threaded to the lower end of said standard and bearing against one of said members, a tubular member surrounding said standard and supported from said base, an annular device surrounding said standard and bearing against said tubular member, said standard having an annular projection engaging with the opposite face of said device, a rod contained within said standard, a spiral spring surrounding said rod and confined between a projection thereon and said nut, and a clamping member secured to said rod.

5. In a device of the class described, a hollow base, a plurality of weight members within said base, a hollow standard extending within the base and through perforations in said weight members, a rod mounted within said standard, a spring on said rod, a combined spring-retaining and base-clamping nut threaded to said standard and having a projecting portion to sustain one end of said spring, retaining means for the other end of said spring, and a clamp attached to the rod.

6. In a device of the class described, the combination of a hollow base, a plurality of circular perforated weight members within said base, a hollow standard projecting within the base and through the perforations in said members, a washer sustained upon the base and surrounding said standard, a tubular member surrounding said standard and supported upon said washer, a circular device engaging the opposite end of said tubular member, an abutment on said standard engaging said device, a nut threaded to said standard and provided with an internal abutment, a rod within said standard provided with a

projection, a spring confined between said abutment and projection, and a clamp secured to said rod.

7. In a device of the class described comprising a hollow base frame member, a sheet metal covering therefor, an internal washer engaging said member, a plurality of weight members within said base adjacent said washer, a hollow standard extending into said base and through said washer and weight members, an internally shouldered nut in threaded engagement with said standard and one of said weight members, a rod within said standard provided with an abutment, a spring confined between said abutment and said nut, and a clamping member secured to said rod and arranged to be drawn within said base by the expansive force of said spring.
- 10 8. In a device of the class described, the combination of a hollow base, a plurality of

stabilizing members within said base, a hollow standard having a circumferential projection and arranged to extend partly within and partly without said base, a shouldered nut threaded to the inner end of said standard and arranged to bear at its upper end against one of said stabilizing members, a rod within said standard provided with an abutment, a spring confined between said nut and said abutment, a hollow member surrounding said standard, one end of said member supported upon the base, a washer confined between the other end of said hollow member and the projection on said standard, and a clamp carried by said rod and arranged to be concealed within the base.

In testimony whereof I have hereunto set my hand this 16th day of September, A. D. 1927.

ANDREW J. CARMICHAEL.
